(57) **CLAIM**

The ornamental design for a set of straps for a wearable device, as shown and described.

DESCRIPTION

FIG. 1 is a top perspective view of a set of straps for a wearable device embodying our new design;

FIG. 2 is a bottom perspective view thereof;

FIG. 3 is a top view thereof;

FIG. 4 is a bottom view thereof;

FIG. 5 is a side view thereof;

FIG. 6 is another side view thereof;

FIG. 7 is a back view thereof;

FIG. 8 is a front view thereof;

FIG. 9 is an enlarged perspective view of a portion of that which is shown in FIG. 1;

FIG. 10 is an enlarged perspective view of a portion of that which is shown in FIG. 2;

FIG. 11 is an enlarged perspective view of a portion of that which is shown in FIG. 1;

FIG. 12 is an enlarged perspective view of a portion of that which is shown in FIG. 2; and,

FIG. 13 is another top perspective view thereof.

Broken lines, where shown, are used to illustrate portions of the set of straps or environmental subject matter that form no part of the claimed design.
